UNITED STATES PATENT OFFICE.

CHARLES WILLMS, OF BALTIMORE, MARYLAND.

FLUSHING-TANK.

No. 850,989.

Specification of Letters Patent.

Patented April 23, 1907.

Application filed December 19, 1906. Serial No. 348,578.

To all whom it may concern:

Be it known that I, CHARLES WILLMS, a citizen of the United States, residing in Baltimore city, State of Maryland, United States of America, have invented certain new and useful Improvements in Flushing-Tanks, of which the following is a specification.

My invention relates particularly to the devices for operating the flush-valves of flushing-tanks; and my improvements are especially adapted for use in connection with flushing-tanks of the kind shown in my United States Patent No. 838,601, of December 18, 1906.

In low-down flushing-tanks the flush-valve is usually operated by means of a handle or push-button located at the lower right-hand corner of the tank; but it is desirable sometimes to locate the push-button in the upper middle portion of the front wall of the tank. According to my present invention I locate the push-button in this way, and I connect the flush-valve, by means of connecting-rods, with a lever pivoted to a bracket attached to the rear wall of the tank, and this lever is provided with an arm engaged by the push-button. The arm is preferably made adjustable, and the bracket may also be made adjustable in order to provide for the proper operation of the flushing-valve. When my improvements are applied to flushing-tanks of the kind shown in my patent before mentioned—that is, a tank made of sheet metal and surrounded by a jacket or condensation-collector, also made of sheet metal—it has been found necessary to make certain changes in the construction of the water-containing tank in order to accommodate the valve-operating lever without losing any water-space in the tank. This I accomplish by forming an opening or fenestrum in the front wall of the water-containing tank near the upper edge thereof and surround this opening with a casing or hood, which while receiving the arm of the valve-operating lever and permitting the lever to operate freely permits the water in the tank to rise above the opening in the front wall of the tank, through which the push-button operates and the arm of the lever vibrates.

In the accompanying drawings, Figure 1 is a perspective view of a flush-tank of the general kind shown in my patent above mentioned with my improvements applied. Cer-

tain parts are shown in section and parts are broken away in order to better illustrate other parts. Fig. 2 shows a transverse section of the upper part of the tank and its equipments. Fig. 3 shows, on a small scale and in rear elevation, the flushing-tank illustrated in Figs. 1 and 2.

The water-containing tank A is of substantially the same construction as that illustrated in my before-mentioned patent, and the jacket or condensation-collector B is also of the same general kind. The cover C is arched, as shown in my patent, and this arched construction of the cover permits the valve-operating mechanism to operate freely, as will be apparent from the further description of this invention.

The ball-cock D and the flushing-outlet E are of the kind shown in my patent and also in my application, Serial No. 340,677, filed October 26, 1906.

The details of construction of the couplings and spacing devices and the particular kind of valve herein illustrated are not claimed herein; but it will be understood that the devices which clamp the ball-cock to the water-tank and its jacket and those that clamp the valve-seat E' to the tank and jacket are adjustable, and there is sometimes some variation in the space between the bottom of the jacket and the bottom of the tank. These features, however, are not claimed herein; but in view of these peculiarities certain adjustments of the valve-operating mechanism are provided for, which are herein claimed.

The valve F, which is claimed in my application above mentioned, has a valve-stem f, passing through a guide f', attached to the front wall of the water-tank, and this valve-stem is connected with a rod F', in turn connected with a valve-operating lever G. This lever is pivotally connected with the front end h of a bracket H, projecting from the rear wall of the tank A. The bracket has a downwardly-projecting flange H', formed with open-ended slots h', through which extend screws I, that engage a nut or plate I', applied to the front face of the flange. There screws extend through holes in the rear wall of the tank A, and between the heads of the screws and the tank are interposed soft washers i and metal washers i'. By means of these devices the bracket is firmly held in

place on the rear wall of the tank, and the bracket may be given any desired vertical adjustment. Ordinarily the bracket is secured to the tank before the latter is placed inside its jacket; but if it is desired to adjust the bracket after the tank has been placed within its jacket it may be readily done, inasmuch as a hole or fenestrum K is formed in the rear wall of the jacket opposite the heads of the screws, and a screw-driver may be easily inserted to loosen the screws and permit of the desired adjustment. In this way also by loosening the screws the bracket H may be withdrawn from the tank and replaced therein without removing the screws or the plate I'. In order to insure the proper movement of the lever to close the valve, I preferably weight it at H².

The push-button L is preferably located in the middle upper portion of the front wall of the tank. Its stem l extends through a bushing l', which is secured to the front wall of the jacket by means of a locking-nut l'', which is preferably faced on its rear side with a washer, of rubber or other soft material l''. To the rear end of the stem of the push-button is secured a convex or rounded buffer L', which engages the downwardly-projecting arm M of the valve-operating lever G.

Opposite the push-button an opening or fenestrum N is formed in the front wall of the tank A, which is of sufficient size to permit the buffer L' to pass in and out and to permit the arm M of the valve-operating lever to vibrate. The lower portion of this opening is some distance below the upper edge of the water-containing tank, and if the water were allowed to rise in the tank above this opening it would flow into the condensation-collector, which is inadmissible. If the water-level is maintained below the opening, the capacity of the tank is reduced to a large extent, which is undesirable. I therefore provide a casing or hood O, which is closed at the bottom on opposite sides and at the rear, as clearly shown in the drawings. It is open at the top to receive the arm M, and it is open opposite the fenestrum N. By this device the water-level in the tank may be located near the upper edge of the tank and above the fenestrum.

The capacity of the tank is therefore not reduced to any appreciable extent. The hood or casing O may be formed in various ways, being of such construction and of such size only as to cover or inclose the fenestrum N and yet permit of the proper operation of the push-button and valve-operating lever.

The arm M is preferably made of round wire bent at right angles, as shown, and it is adjustably secured by a set-screw o to the front end of the valve-operating lever. By the devices shown the arm may be adjusted back and forth to vary its length relatively to the pivot of the valve-operating lever, and it may be also turned in such manner as to

move laterally its lower front end. The adjustment of the arm lengthwise will vary the vertical movement given to the flush-valve F. In this way the valve may be lifted to any desired extent. This adjustment may be used in connection with the adjustment of the bracket H or may be used independently thereof.

It will be observed that the buffer L' is convex and engages the rounded end of the arm M. The contacting surface is therefore very small, and a minimum amount of friction is produced. As the push-button is moved back and forth the arm M follows the rounded surface of the buffer easily and with little friction; but sufficient force is always produced to give proper movement to the flushing-valve. It is desirable that the arm should contact with the middle portion of the buffer, and by means of the adjusting devices referred to the arm may be moved laterally or back and forth to bring its lower end into proper relation with the buffer even though it may not be in such proper relation when the parts are at first assembled.

I have shown and described the best way now known to me of carrying out my invention; but some parts of my invention may be used without the other parts, and some of the mechanism may be differently arranged. I prefer to locate the bracket for supporting the flush-valve-operating lever on the rear wall of the tank, because, among other advantages, I can more easily adjust the bracket when it is thus located; but the bracket may be secured elsewhere and yet be within the scope of some parts of my invention.

By employing an arched cover I can locate the valve-operating lever high up in the tank and give proper movement thereto without coming in contact with the cover.

I claim—

1. The combination of a water-tank, a jacket surrounding it but leaving an air-space between it and the tank both at the bottom and around the sides, a bracket secured to the rear wall of the tank, a flush-valve, a valve-operating lever connected therewith and pivoted to the bracket and having an arm extending downwardly to a position between the tank and the jacket and a push-button operating through the front wall of the jacket and engaging said downwardly-projecting arm on the valve-operating lever.

2. The combination of a water-containing tank having an opening or fenestrum in its front wall, a hood or casing surrounding this opening but open at the top, a bracket secured to the rear wall of the tank, a valve-operating lever having an arm extending into the hood, a flush-valve connected with said lever and a push-button operating through the front wall of the tank and engaging the arm of the lever in the hood.

3. The combination of a flush-tank, a

bracket secured thereto and adjustable vertically thereon, a valve-operating lever pivoted to the bracket, a flush-valve connected therewith, an adjustable arm carried by said 5 valve-operating lever and a push-button operating through the front wall of the tank engaging said adjustable arm.

4. The combination of a flush-tank having an opening or fenestrum in its front wall, a 10 hood inclosing said opening but open at the top, a bracket attached to the rear wall of the tank opposite the fenestrum therein, a valve-operating lever pivotally connected with the bracket, a flush-valve connected therewith 15 and a lever-arm adjustable both longitudinally and about its axis on the valve-operating lever and which extends down into the hood and a push-button operating through the front wall of the tank engaging said lever-arm.

5. The combination of a water-containing tank having an opening or fenestrum in its front wall a jacket surrounding the tank and having a fenestrum in its rear wall, a hood or 20 casing inclosing the fenestrum in the front wall of the tank, a bracket secured to the rear wall of the tank opposite the opening in the rear wall of the jacket, a flush-valve, a valve-operating lever connected therewith 25

pivoted to the bracket, and a push-button 30 operating through the front wall of the jacket and engaging the valve-operating lever.

6. The combination of a water-tank, a 35 flush-valve, a jacket surrounding the tank and having an opening in its rear wall, a bracket secured to the tank opposite the opening in the rear wall of the jacket, a valve-operating lever connected with the flush-valve and a push-button operating through the front wall of the tank engaging said lever. 40

7. The combination of a water-tank having an opening or fenestrum in the upper portion of its front wall, a hood or casing surrounding this opening, a jacket surrounding the tank, a push-button operating through 45 the front wall of the jacket, a bracket secured to the tank, a flush-valve, and a valve-operating lever pivoted to the bracket and having an arm extending into the fenestrum in the front wall of the tank and engaged by the 50 push-button.

In testimony whereof I have hereunto subscribed my name.

CHARLES WILLMS.
